UNITED STATES PATENT OFFICE.

JOSEPH FRENCH, OF WOONSOCKET, RHODE ISLAND.

PRINTING AND INKING DEVICE FOR POSTMARKING AND CANCELING MACHINES.

SPECIFICATION forming part of Letters Patent No. 700,414, dated May 20, 1902.

Original application filed January 23, 1901, Serial No. 44,490. Divided and this application filed April 1, 1901. Serial No. 53,986. (No model.)

To all whom it may concern:

Be it known that I, JOSEPH FRENCH, a citizen of the United States, residing at Woonsocket, in the county of Providence, State of Rhode Island, have invented a certain new and useful Improvement in Printing and Inking Devices for Postmarking and Canceling Machines, of which the following is a specification, reference being had therein to the accompanying drawings.

The invention consists in improved printing devices and inking arrangements therefor, which have been devised for use more especially in machines for postmarking and canceling purposes in connection with cards, letters, and the like or for printing upon cards, &c.

The present invention is a division of that which is presented in my application for United States Letters Patent, filed January 23, 1901, Serial No. 44,490.

In the drawings, Figure 1 is a plan view of portion of a postmarking and canceling machine such as is presented in my application aforesaid, the printing-roll being omitted for the sake of clearness and the periphery thereof being indicated by a dotted circle. Fig. 2 shows the printing-roll in plan detached. Fig. 3 shows the same in elevation. Fig. 4 is a vertical cross-section thereof. Fig. 5 is a vertical cross-section on the plane indicated by the dotted line 5 5, Fig. 4.

Having reference to the drawings, 74 designates the printing-roll, (indicated by a dotted circle in Fig. 1,) and 75 the backing-roll, which co-operates therewith. The cards or other articles to be postmarked or printed pass between the said two rolls.

The inking-roll is shown at 232, Fig. 1, it being mounted on a vertical spindle 233, which is carried by the horizontal swinging arm 234, the latter being mounted to rock on a vertical pin or post 235. A second arm is shown at 236, it being independently mounted upon the said post or pin and being furnished with a roll 237, which works in connection with the periphery of a cam 238, rotating in unison with the printing-roll 74. The purpose of the cam 238 is to hold the inking-roll 232 away from the periphery of the printing-roll 74 except at such times as the printing-sur-

faces of the latter are presented in position to have ink applied to the same by the inking-roll 232. The cam 238 acts more directly to move the roll-carrying arm 236, and the outward movement of the latter is transmitted to the arm 234, on which the inking-roll 232 is supported. A contracting spiral spring 239, connected with a projecting portion 260 of the carrying-arm 234 of the inking-roll 232, acts with a tendency to bear the inking-roll 232 toward the printing-roll 74. The effects of this spring 239 are also transmitted to the other arm 236, with the effect of carrying the antifriction-roll 237 on said arm 236 toward the periphery of the cam 238. If the construction were such as to permit the antifriction-roll 237 to leave the surface of the cam 238—for instance, at those times when the surface of the inking-roll 232 is in contact with the printing-surface of the printing-roll 74—there would be a distinct blow when the cam 238 and roll 237 again come in contact with each other, which would produce a hammering in the working of the machine. It is for the purpose of obviating this hammering which would be incident to the renewed contact of the cam 238 and roll 237 with each other that I employ the two separate arms 234 and 236. I interpose between the said arms an expansion spiral spring 240, which acts with a tendency to force the two arms 234 and 236 away from each other. This spring 240 is weaker than the main spring 239, and consequently so long as the more prominent portion of the cam 238 is in contact with the antifriction-roll 237 the said main spring 239 is permitted to act with sufficient force to compress the expansion - spring 240. When the inward movement of the arm 234, carrying the inking-roll 232, is arrested by contact of the inking-roll 232 with the printing-surface of the printing-roll 74, the expansion of the spring 240 operates to occasion an independent movement of the second arm 236, thereby maintaining the antifriction-roll 237 in continuous contact with the surface of the rotating cam 238. The drop or depression of the said cam 238 is considerably greater than actually is required to enable the surface of the inking-roll 232 to touch the printing-surface of the printing-roll 74. The object of this is to give

such an excess of inward movement to the second arm 236 as to enable the latter to wholly clear the carrying-arm 234 of the inking-roll 232, and thereby allow the inking-roll 5 232 perfect freedom to take bearing against the printing-surface of the printing-roll 74. In order to avoid shock and hammering between the two arms when the second arm 236 in its outward movement again picks up the 10 roll-carrying arm 234, I interpose a cushion 241 of blow-absorbent material between the two arms. Either rubber or leather may be employed, although other substances may be substituted.

15 In consequence of use the material constituting the ink-absorbent portion of the inking-roll wears away, thus reducing the diameter of the said roll. For the purpose of compensating for this wear and reduction of 20 diameter I employ provision for adjustment between the two arms. In the present instance I place the blow-absorbent cushion 241 in a cup or socket 242, which is placed within a recess of the roll-carrying arm 234, the said 25 cup or socket having a threaded stem 243, which is fitted to a threaded hole in the said arm 234, it having a lock-nut 244 applied thereto. By turning the cup or socket 242 the cushion 241 may be caused to project 30 more or less, and thereby the extent of movement of the two arms 234 and 236 relative to each other may be regulated as required in order to compensate for wear as aforesaid.

The provisions for adjustment which have 35 just been described also enable me to vary as desired the amount of printing-surface measured circumferentially of the printing-roll 74 to which ink is applied. This enables me to vary as desired the length of the imprint 40 which is made by the printing-roll 74 upon the card or other article that is passed through the machine. For example, assuming that the printing-roll 74 is provided with a line or lines of characters to print the place, date, 45 and time of cancellation and below the same with a series of bars 262 or the like for purposes of cancellation, this latter series being equal in length to the longest line of letters or numerals which is likely to be required, it is 50 possible by the adjustment of the cushion 241 aforesaid to so time the contact of the inking-roll 232 with the printing-surface of the printing-roll 74 that it shall come in contact with the said printing-surface just at the beginning 55 of the particular line of letters which is in use for the time being and pass out of contact with the said surface just at the end of the said line, however much the length of the line may vary. By this means only that portion 60 of the series of canceling-bars will be caused to print which agrees with the line of letters or characters for the time being in use above the same.

In the case of the illustrated printing-roll 65 the printing characters which require occasional or frequent change instead of being on removable type are provided on type-wheels

or the equivalent thereof, which are movably combined with the printing-wheel, so that by simple shift of the same without removal they 70 may be arranged to print any required date or hour. Figs. 2 to 5 show an arrangement in which the name of a city and that of a State, as well as the number of a year, are permanently affixed to the main portion or body of 75 the printing-roll, although it should be explained that these are formed on or applied to plates 245, which are detachably secured by bolts 261 261 to the printing-roll 74, so that when occasion requires they may be removed 80 and replaced by others. The characters for printing the date and hour of cancellation are shown provided on a series of type-wheels 246 246, which are mounted upon a pin 247, having its ends suitably supported on the printing- 85 roll. For the purpose of holding the wheels 246 246 locked after having been adjusted into the desired position a series of dogs 248 248 is provided, one for each wheel, each dog 248 being notched to receive the end of each of the projecting type on its wheel, as indicated in Fig. 3, as such type are brought around into position for engagement therewith in succession and being acted upon by an expansion spiral spring 249, that is compressed between the body of 90 the dog 248 and a bar 250, extending across the series of dogs above the same. Each dog has an upwardly-extending projection 251, by means of which the dog 248 may be lifted by hand when it is required to rotate the corresponding type-wheel 246 for the purpose of readjustment. The type-wheels are mounted to rotate in planes extending parallel with the axis of the printing-roll. The assembly 95 of type-wheels is barrel-shaped—that is to say, the wheels are of varying diameters and the type are curved transversely on a radius slightly greater than that of the printing-roll, so that a given series of characters brought into line at the periphery of the printing-roll 100 74 will correspond truly in curvature with the periphery of the said roll or at any rate will be concentric with the roll 74. This secures an even and uniform imprint. The face of the type are straight vertically to insure flat 105 contact with the surface on which the printing is to be effected. The type-wheels are all mounted with their axis in line with one another, and the characters thereon which are to participate in making the desired imprint 110 come into one straight line with the fixed characters on the roll itself.

I do not claim the construction of the type-wheel herein, inasmuch as the same is to be made the subject of claims in a divisional application.

What I claim is—

1. In combination, the printing-roll, the inking-roll, a carrier for said inking-roll, means to press the inking-roll toward the printing-roll, a cam rotating in unison with the printing-roll, a movable member intermediate the surface of said cam and said carrier, means to hold said member in continuous contact

with the surface of said cam while the inking-roll is in contact with the printing-surface of the printing-roll, and a yielding cushion between said carrier and movable member to relieve the shock when the two come together after being separated, substantially as described.

2. In combination, the printing-roll, the inking-roll, a carrier for said inking-roll, means to press the inking-roll toward the printing-roll, a cam rotating in unison with the printing-roll, a movable member intermediate the surface of said cam and said carrier, a spring interposed between said carrier and said movable member and operating to hold said member in continuous contact with the surface of said cam while the inking-roll is in contact with the printing-surface of the printing-roll, and a yielding cushion between said carrier and movable member to relieve the shock when the two come together after being separated, substantially as described.

3. In combination, the printing-roll, the inking-roll, a carrier for said inking-roll, means to press the inking-roll toward the printing-roll, a cam rotating in unison with the printing-roll, a movable member intermediate the surface of said cam and said carrier, means to hold said member in continuous contact with the surface of said cam while the inking-roll is in contact with the printing-surface of the printing-roll, a yielding cushion between said carrier and movable member to relieve the shock when the two come together after being separated, and means to adjust the said cushion in the plane of movement of the carrier and movable member, substantially as described.

4. In combination, the printing-roll, the inking-roll, a carrier for said inking-roll, means to press the inking-roll toward the printing-roll, a cam rotating in unison with the printing-roll, a movable member intermediate the surface of said cam and said carrier, a spring interposed between said carrier and said movable member and operating to hold said member in continuous contact with the surface of said cam while the inking-roll is in contact with the printing-surface of the printing-roll, a yielding cushion between said carrier and movable member to relieve the shock when the two come together after being separated, and means to adjust the said cushion in the plane of movement of the carrier and movable member, substantially as described.

5. In combination, the printing-roll, a cam rotating in unison therewith, the inking-roll, an arm carrying the said inking-roll, an arm operated by the said cam, a yielding cushion between the two arms, and a spring tending to separate the two arms, substantially as described.

6. In combination, the printing-roll, a cam rotating in unison therewith, the inking-roll, an arm carrying the said inking-roll, an arm operated by the said cam, a yielding cushion between the two arms, means to adjust the said cushion in the plane of the two arms, and a spring tending to separate the two arms, substantially as described.

In testimony whereof I affix my signature in presence of two witnesses.

JOSEPH FRENCH.
